Attorney

UNITED STATES PATENT OFFICE.

RAYMOND McDougall, of MELBOURNE, VICTORIA, AUSTRALIA.

DETACHABLE GARMENT-SECURING DEVICE FOR WAR-RIBBONS.

1,235,580.

Specification of Letters Patent.

Patented Aug. 7, 1917.

Application filed February 29, 1916. Serial No. 81,167.

To all whom it may concern:

Be it known that I, RAYMOND McDougall, a subject of the King of Great Britain, and residing at 279 Little Collins street, Melbourne, State of Victoria, Commonwealth of Australia, have invented a certain new and useful Improvement in Detachable Garment-Securing Devices for War-Ribbons, of which the following is a specification.

10 This invention relates to an improved device for holding and detachably securing war ribbons and like decorations to a garment and it has been devised with the object of providing simple and conveniently operated means whereby a ribbon or ribbons can be mounted in an attractive manner and can be removed from and replaced on the device in a very easy and rapid manner.

15 The ordinary method of mounting ribbons is to fold them around a piece of flat material and then stitch the edges together to draw the ribbon tightly on the stiffening material. The ribbon so mounted is sewn or secured to a garment by eyes or a clasp fitted to or formed on the stiffening material.

20 The above mentioned method of mounting the ribbon has the disadvantage of necessitating time in the accomplishment and the use of a needle and thread for stitching the 30 ribbon. Moreover, a ribbon mounted as above described cannot be removed and replaced conveniently when it becomes soiled or worn.

Now my invention obviates the disadvantages above described as by its use one or 35 more pieces of ribbon can be securely mounted on a holding device and removed therefrom when desired in a very rapid and convenient manner.

40 The invention broadly consists in the provision of a simple form of ribbon holding bar formed with rolled or turned edges and in the combination therewith of plates and revoluble studs or the like which are constructed and arranged whereby the ends of a 45 ribbon can be detachably clamped between the said plates and the rolled or turned edges of the bar. The construction and arrangement of the parts forming the improved device permit of it being readily attached to and detached from a garment without necessitating the use of any implements or tools.

In order that the details of construction

and operation of the invention may be more 55 clearly understood, reference is made to the accompanying sheet of drawings wherein:—

Figures 1 and 2 are views in perspective of a device constructed in accordance with the present invention and designed for carrying two ribbons.

Fig. 3 is a view in perspective showing the device viewed from the back with the parts at one end unassembled and the parts at the opposite end assembled and secured to a 65 piece of cloth.

Fig. 4 is a view in perspective of the improved ribbon bar.

Fig. 5 is a view in cross section of Fig. 4 taken on the dotted line I—I, and Fig. 6 is 70 a detail view showing a modified form of plate.

In these drawings like characters of reference have been employed to indicate similar or corresponding parts in the different 75 views, and the letter *a* designates the ribbon bar which is shaped out of sheet metal or other approved material by means of stamping tools or the like.

The ribbon bar is formed with a recess or 80 channel on one side and this said recess can be made by bending over the upper and lower edges of the material forming the bar and providing the said edges with oppositely disposed beads *b*. The bar shown in 85 the drawings is adapted to hold two ribbons *c* and *d*, but it will be obvious that it can be made in various sizes to hold one or any number of ribbons.

The back of the ribbon bar is provided 90 with studs *e* which are formed with flattened heads *f* having holes *g* therein. The heads of the studs *e* preferably are pointed to permit of them being easily passed through a piece of cloth for the purposes 95 hereinafter described.

A stud *e* is located at the center of each section of ribbon *c* and *d* and its shank portion is revolvably mounted in the bar so that it can be rotated from the position shown in 100 the left-hand end of Fig. 3 to the position shown in the right-hand end of the same figure.

The pieces of ribbon *c* and *d* passed around the ribbon bar are securely fastened 105 thereto by plates *h* which are passed over and retained in position by the studs *e*. The said plates *h* are provided with slot-

ted holes *i* which permit of them passing over the studs *e* when the heads of the same are placed in line with the ribbon bar.

The plates *h* normally fit neatly between 5 the beads on the recessed side of the ribbon bar and when a ribbon is folded around said bar its sides are sprung open slightly when the said plates are being pressed in between said beads.

10 The holes *g* in the studs *e* are to receive split pins *j* for securely fastening the ribbon bar to a jacket or the like garment, part of which is shown at *k* in Fig. 3 of the drawings.

15 The mode of assembling the parts of the invention to secure the ribbons *c* and *d* thereon and to secure the device to a garment is as follows:—The ribbons *c* and *d* are folded around the bar *a* with their ends 20 overlapping the beads *b* as shown in the left-hand end of Fig. 3. The heads *f* of the studs *e* are turned into line with the ribbon bar (see Fig. 4) and the plates *h* are passed over the said studs and pressed 25 in between the beads *b* on the edges of said bar. The said plates are made sufficiently wide to necessitate a fair amount of pressure to cause them to be squeezed between the beads *b* and this results in the ribbons 30 being drawn tightly around the ribbon bar *a*. When the plates *h* have been forced into position the heads of the studs *e* are turned to right angles with the ribbon bar and thereby 35 securely fasten the plates and ribbons in position (see Fig. 2).

The ribbons *c* and *d* and plates *h* having been secured to the ribbon bar *a* as above described, the said bar may then be attached to a coat or other garment by forcing 40 the heads of the studs *e* through the cloth of the same and then passing the split pins *j* through the holes *g*, as shown in the right-hand end of Fig. 3 of the drawings.

The ribbon bar can be readily removed 45 from a coat or other garment to which it has been secured and its parts detached by reversing the order of operations above described.

A ribbon bar constructed as above 50 described will have a neat appearance and can be easily manipulated to permit of a ribbon being reversed or replaced when it becomes soiled or worn.

If preferred one plate *h* (Fig. 6) can be 55 employed to secure two or more pieces of ribbon to a bar and a plurality of studs *e* may be arranged to pass through a plurality of holes *i* in each plate.

It will be readily obvious that various constructional modifications and alterations 60 may be made in the ribbon bar and that the same may be fastened to a coat or other garment by a brooch pin or other means without departing from the spirit and scope of the invention as set out in the following 65 claiming clauses.

Having thus described my invention what I claim as new and desire to secure by Letters Patent is:

1. A device for detachably mounting and 70 securing war ribbons and like decorations to garments, comprising a bar having turned edges forming beads, headed studs pivotally mounted on said bar, and a plate having slots through which the studs pass in order 75 to secure the plate in position.

2. A device for detachably mounting and 80 securing war ribbons and like decorations to garments, comprising a bar having a recess on one side to receive the ends of the ribbon folded around the bar, a plurality of studs pivoted on said bar and formed with flattened and pointed heads having 85 holes therein, and a plurality of plates having slots fitting into the recess of the bar, the heads of the studs passing through the slots and when turned securing the plates in position.

3. A device for detachably mounting and 90 securing war ribbons and like decorations to garments, comprising a bar having turned edges forming beads, headed studs pivotally mounted on said bar, a plate having slots through which the studs pass in order to secure the plate in position, the heads of said 95 studs being of pointed shape so as to be capable of separating the fibers of a fabric and passing readily therethrough, and means for securing said heads at the rear of the fabric.

4. A device for detachably mounting and 100 securing war ribbons and like decorations to garments, comprising a bar having turned edges forming beads, headed studs pivotally mounted on said bar, a plate having slots 105 through which the studs pass in order to secure the plate in position, the heads of said studs being of pointed shape so as to be capable of separating the fibers of a fabric and passing readily therethrough, and being 110 formed with holes therein, and means adapted to pass through the holes in said stud heads in order to secure the same when passed through the fabric.

R. McDougall.
